UNITED STATES PATENT OFFICE.

J. MORTIMER GOLDSMITH, OF BOSTON, MASSACHUSETTS.

VALVE.

SPECIFICATION forming part of Letters Patent No. 297,986, dated May 6, 1884.

Application filed July 24, 1883. (No model.)

To all whom it may concern:

Be it known that I, J. MORTIMER GOLDSMITH, of Boston, county of Suffolk, State of Massachusetts, have invented an Improvement in Valves, of which the following description, in connection with the accompanying drawings, is a specification, like letters on the drawings representing like parts.

My invention relates to that class of valves known as "straight-way valves," commonly employed for steam, water, and oil, and has for its object to improve their durability and cheapen their construction, and enable them to be self-packing, and to be operated quicker and more easily, the valve being so constructed that by one movement of a lever it may be opened gradually from its finest flow to a full pipe area, and be closed instantly whenever required, which cannot be done with a screw-operated valve. In this my improved valve the valve-segment covering the seat of the valve-outlet never leaves its seat, and when not subjected to fluid-pressure is held against its seat by a suitable spring, so that it is impossible for sediment or foreign matter to lodge between the seat and valve-segment and cut or wear the same. In my valve, when closed, the greater the pressure the closer the contact between the valve-segment and its seat, and consequently the tighter the valve. To facilitate and render easy the movement of a large valve-segment, the frictional resistance of which is in proportion to the pressure, I have provided the main valve-segment with an auxiliary valve-segment adapted to cover and uncover one or more small ports made in the main valve-segment, to thus more nearly equalize the pressure at each side the main valve-segment before it is moved to uncover the valve-outlet. The valve-segment is moved on its seat by a head having a guided stem, and provided with a transverse central way and with suitable projections to engage the said segment. The projections for moving the valve-segment are so placed with relation to the way in the said head as to leave the way unobstructed when the valve-segment is in position to uncover the outlet. The head referred to has a conical shoulder, which is pressed into a conical seat attached to a hub

of the cap, and preferably by one or more springs, as will be described.

My invention consists in a straight-way valve case or shell having a cylindrical seat, and a valve-segment placed therein loosely, 55 combined with a head inserted therein and provided with a stem, a way, and with suitable projections to engage and move the said valve against the said seat, the said loose valve-segment being free to be pressed against 60 the valve-seat by a force measured by the pressure of fluid in the shell of the valve.

My invention also consists in a valve-shell having a cylindrical seat, and a loose valve-segment adapted to be pressed against the said seat by the pressure of the fluid in the said valve-shell, combined with a head having a stem and a way, and with projections located in such position with relation to the said way and the valve-outlet that the said head, when 70 turned to move the valve-segment to uncover the valve-outlet, shall place the way in the head in line with the valve-outlet.

Figure 1 represents in vertical section a valve embodying my present improvements; 75 Fig. 2, a horizontal section of the entire valve in the dotted line $x\ x$, Fig. 1; Fig. 3, a similar section on the dotted line $x'\ x'$; Fig. 4, a back view of the main valve-segment, and Fig. 5 a like view of the auxiliary valve-segment.

In the drawings, A represents the valve shell or case, A' its inlet, and A'' its outlet end. The shell or case is bored out cylindrically to form a valve-seat, b, against which slides the 85 convex-turned face of the main valve-segment c, the said segment being placed in the valve-case loosely, so that the pressure of the fluid to be controlled by the valve measures the pressure of the said main valve-segment against 90 its seat b, when the outlet of the valve is closed by the segment, the greater the fluid-pressure the closer the fit. In a large valve this pressure is so great as to make it quite difficult to move the main valve-segment; so for such 95 valves I provide the main valve-segment with one or more ports, 2, and turn its back for the reception against it of the turned face of a smaller auxiliary valve-segment, c' , which has suitable shoulders or projections, 3, at its rear 100

side, which are adapted to be engaged by projections d of the rotating head or valve-mover B. This valve-mover B is provided with a way or passage, B', for the fluid, and has a stem, B², extended outward through the cap or cover C, where it has applied to it a handle, B³, by which to turn the said head and slide the valve-segment on its seat to uncover or cover the outlet of the valve. As shown in Fig. 2, where the outlet is uncovered, movement of the head B in the direction of the arrow 16 near it will cause the projections d in engagement with the projections 3 on the auxiliary valve-segment to slide the latter on its seat (the back of the main valve-segment) until the end of the valve-segment c² strikes the pin or projection 5 of the main valve-segment, and thereafter the main valve-segment c will be moved in unison with it until the stop pin or projection 6, carried by the foot 7 of the head B, (which foot is fitted into a socket, 8, of the case,) meets the shoulder 9, formed at one end of a recess, 10, made in the annular support 12, on which the end of the main valve-segment rests and moves, when the further movement of the head and valve will be arrested. As the auxiliary valve-segment is moved from its position, Fig. 2, against the stop 5, it closes the port 2 of the main valve-segment. While the valve-segments are in the position, Fig. 2, a suitable spring, e, between the back of the segment c² and the side of the head, and with its ends abutted against the projections or shoulders 3 at the back of segment c², keeps the face of the valve-segment c in contact with the seat b, and also keeps the two valve-segments pressed together, so that the valve-segment c does not retire or draw back from its seat, as is the case with a valve-disk operated by a screw, and consequently there is no opportunity for the entrance of grit, dirt, or foreign matter between the main valve-segment and the seat b to wear them. The edges of the sliding valve-segments act to clean the seats on which they rest. When the main valve-segment acts to close the main outlet of the valve-case, its port 2 is closed by the auxiliary valve-segment c², and the main valve-segment is thrust against the seat b by a force measured by the pressure of the fluid on the back of the said valve-segment.

To start the main valve-segment and uncover the outlet of the case A, the hub B is turned in a direction opposite the arrow 16, Fig. 2, to move the auxiliary valve-segment far enough to place the port 17 thereof in line with the port 2 of the main valve-segment, which thus permits the fluid to pass beyond the said main valve-segment and relieves it from its great pressure on the seat b, and in its further movement the end of the said auxiliary valve-segment strikes the pin or projection 18 of the main valve-segment, and slides it around on the seat b to uncover the outlet A², and, as the edge of the said main valve-segment

uncovers the said outlet, the way B', made transversely through the head B, comes gradually into line with the inlet and outlet ends of the case, making a substantially straight way. 70

Thus far I have described a valve having a main and an auxiliary segment, it being such as I prefer to use in valves of any considerable size, or employed for very high pressures; but it will be understood that the auxiliary valve-segment may be omitted, and to do so and produce a valve with but the segment c it is only necessary to prolong the projection d, so as to strike the projections 5 and 18, or otherwise suitably engage the said valve-segment, its 75 port 2 being of course closed, and with but this one valve-segment the ends of the spring e, of suitable length, will abut against the projections 5 and 18, and will be thereby rigidly held.

The foot 7 of the head B is shown as chambered to receive a spring, f, which rests at one end against the case A, and acts to press the conical part 20 of the head into the conical seat made in the hub 21, preferably cast with the cap C, the said conical seat and conical part 20 having suitable passages and grooves, 22 23, for the reception of the material controlled by the valve, which, entering therein, serves as a lubricant, or to avoid setting of the parts, such construction enabling the valve-stem about the case to be made close without the employment of the usual stuffing-box and packing. 85

To increase the closeness of fit between the part 20 and its conical seat, I have provided the stem B² with a screw-thread at 24, upon which, after applying the spring 25, I have screwed a nut, f', by turning which the effective force of the said spring may be increased or diminished. 90

Between the upper end of the shell A and cap C, I insert a piece of suitable packing, g, it being placed in an annular groove formed, preferably, in the plate C. 95

It will be noticed that the projections which move the segment or segments are so placed on the side of the head or valve-mover B that when the valve-segment c uncovers the outlet of the valve-case the way B' is brought into and remains in line with the inlet and outlet 100 of the case A. 110

I have thus far described the main valve-segment as held against the outlet-passage of the seat b to check the flow of fluid through the valve-shell, and while I greatly prefer such construction it will be understood, should the spring e be made sufficiently stiff to overcome the pressure of the fluid, then in such case the valve-segment may be employed to cut off the fluid at the part of the seat b next or about 115 the inlet of the case, the recess 10 and stoppin 6 being suitably located to permit such change; and it will also be understood that I may, if desired, without departing from my invention, employ two or three valve-segments 120 like that marked c, or two or three sets of segments like those marked c and c². 130

By the use of two segments opposite each other I may simultaneously open and close both an outlet and an inlet, and by the use of three independent segments I may adapt my 5 invention for use as a three-way valve.

I claim—

1. In a straight-way valve, a case or shell having a cylindrical seat, *b*, a valve-segment placed therein loosely, a head or valve-mover 10 also in said shell, having a stem and a transverse fluidway or port, a spring interposed between said valve-segment and valve-mover, and projections on the two to engage such segment and its mover, all combined and arranged 15 substantially as described.

2. The valve-case having the cylindrical seat *b*, a main valve-segment provided with a port, and an auxiliary valve-segment seated on the 20 said main valve-segment, combined with the head or valve-mover provided with the transverse way *B'*, and with means to move the said valve-segments in succession, as and for the purposes described.

3. The valve-case and valve-segment inserted 25 therein loosely, and the head or valve-mover provided with a suitable way for the passage of the fluid, combined with a spring to keep the valve-segment against the valve-seat *b*, substantially as described.

30 4. The valve-case provided with the cylindrical seat *b* and recess 10, and valve-segment

inserted therein loosely, combined with the head or valve-mover provided with the way 35 *B*, and with a pin or projection, 6, and adapted to move the said valve-segment, substantially as described.

5. The valve-case and its cap provided with the hub 21, extended into the said shell, and having passages 22, combined with the head 40 *B*, provided with the conical part 20, having grooves, and with a spring to keep the said part 20 into the conical seat in the said extended hub, substantially as described.

6. The valve-case and its cap provided with the hub 21, extended into the said shell, and having passages 22, combined with the head 45 *B*, provided with the conical part 20, having grooves, and with a nut to regulate the force of the said spring, substantially as described.

7. The valve-segment provided at its rear 50 side with projections or shoulders, combined with a flat spring, *e*, having its ends abutted against the said shoulders, substantially as described.

In testimony whereof I have signed my name 55 to this specification in the presence of two subscribing witnesses.

J. MORTIMER GOLDSMITH.
